UNITED STATES PATENT OFFICE

GEORGE F. HAUF, OF CHICAGO, ILLINOIS, ASSIGNOR TO CHICAGO METAL MFG. CO., OF CHICAGO, ILLINOIS, A CORPORATION OF ILLINOIS

DRYING TRAY

Application filed August 13, 1930. Serial No. 474,989.

My invention relates to drying trays. It will be explained as embodied in a tray particularly adapted for the drying of hides and the like although it may have a variety 5 of other uses.

One of the objects of my invention is the provision of a tray which is of rugged construction so that it will withstand long and continuous usage without damage or deterioration and which is adapted to be stacked with many other similar trays for the drying of hides and the like in a kiln.

A further object of the invention is the provision of a tray of the character specified 15 which is so constructed that it affords direct contact of circulating air to both sides of the material thereon and which facilitates the attachment thereto and detachment therefrom of hides and the like to be dried.

Other objects and advantages will herein-after appear.

In the accompanying drawing:

Fig. 1 is a perspective view of a number of trays arranged in a stack; 25 Fig. 2 is an enlarged fragmentary elevation of a tray shown partly in section to more clearly illustrate my invention; and

Fig. 3 is a fragmentary section through a portion of the drying element or table and 30 through one of the spacing members of a tray, showing a portion of an adjacent tray in broken lines to illustrate how the spacing member holds adjacent trays separated.

In general, my improved drying tray comprises a foraminous flat table or drying element and a plurality of leg-like spacing members attached thereto and which serve to support the table in spaced relation from any platform or from other similar trays.

The table or drying element 11 is preferably formed of a sheet of relatively heavy gauge metal provided with a large number of perforations or apertures 12 through which air may readily circulate and thereby 45 have direct contact not only with the upper surface but also with the lower surface of a hide 13 which is supported thereon to be dried. The apertures or foramina 12 may also be utilized, in some such manner as 50 shown in Fig. 2, to facilitate the proper at-

tachment to the table of hides in stretched condition for drying. Thus these foramina are adapted to receive the hook ends 14 of stretching clips 15, the other ends of which engage or grip the hide 13 at 16 for holding the same relatively smooth and straight in a position, shape and condition of stretch in which it is desired to have it dry and become set.

The edges of the table are bent downwardly 60 to form relatively deep reinforcing flanges 17. These flanges preferably have their lower margins return bent into folds 18 which provide a smooth lower surface 19 by which the trays may be readily handled. 65 Each corner of the table or drying element is provided with a leg-like support and spacing member 21 of angular form to embrace flanges 17 in the region of the corners. Thus the flanges 17, where they approach a corner 70 of the table, are securely tied together by the spacing members 21, each of which includes an angular vertical flange portion 22 secured to the flanges 17, preferably by spot welding at 23. Each of these leg-like spacing members, which is preferably formed from sheet metal, has its mid-portion bent inwardly to provide an upper shoulder 25, an inwardly offset vertical spacer section 26, a lower angular inverted shoulder 27 and a 80 lower flange 28. The lower flange 28 is parallel to and slightly outwardly offset from the plane of upper flange 22 so as to receive within it the upper flange 22 of a tray therebelow. Thus the upper flange and shoulder 85 22-25 serve to reinforce and strengthen the corner of the tray, to carry the table or drying member thereof and to facilitate the attachment of the table to the spacing member; the lower flange and shoulder 28-27 90 serve to form a socket for the reception of the top of a lower tray whereby the trays are guided in the stacking operation and, in effect, nested in such a way that lateral shifting is prevented and the rigidity and stability 95 of a stack is insured; and the intermediate spacing section 26 insures the desired spacing between trays to afford proper circulation of the drying medium.

Unless the tray is of large size or the 100

weight to be carried thereby is excessive or thin gage metal is employed, four supporting-spacing members, one at each corner, will usually suffice. But if additional members are required or desired one or more spacing members 31 intermediate the corners may be provided. These intermediate members are of identical construction to those for the corners except that they are not angular in the sense of passing around a corner but are shaped as illustrated for the purpose of being secured on the flanges 17 at intermediate points.

It will be understood by those skilled in the art that various modifications may be made in the drying tray as illustrated in the drawing without departing from the spirit of my invention and I desire therefore to avail myself of such modifications as come within the scope of the appended claims.

I claim as my invention:

1. A drying tray comprising a sheet metal drying element, said element including relatively wide reinforcing flanges on the edges thereof bent out of the plane of the drying element, spacing members adapted to support the tray on and in spaced relation to an adjacent tray, said spacing members comprising a vertical portion fixed to the face of said reinforcing flange, an offset shoulder engaging the edge thereof for supporting the same, a spacing portion, a bearing portion adapted to rest on the margin of a similar drying tray, and an offset guide portion depending from said bearing portion.

2. A drying tray comprising a sheet metal drying element, said element including relatively wide reinforcing flanges on the edges thereof bent out of the plane of the drying element, spacing members fixed to said drying element about the margins thereof and adapted to engage the drying surface of a like adjacent tray and hold the trays in spaced relation, said spacing members comprising a vertical portion fixed to the face of said reinforcing flange, an offset shoulder engaging the edge thereof for supporting the same, a spacing portion, a bearing portion adapted to rest on the margin of a similar drying tray, and an offset guide portion depending from said bearing portion.

3. A drying tray comprising a sheet metal drying element, said element including relatively wide reinforcing flanges on the edges thereof bent out of the plane of the drying element, return bent flanges on the first said flanges, and the means for spacing the tray from the drying surface of a like adjacent tray, said spacing members comprising a vertical portion fixed to the face of said reinforcing flange, an offset shoulder engaging the edge thereof for supporting the same, a spacing portion, a bearing portion adapted to rest on the margin of a similar drying tray,

and an offset guide portion depending from said bearing portion.

4. A drying tray comprising a sheet metal drying element, said element including relatively wide reinforcing flanges on the edges thereof bent out of the plane of the drying element, return bent flanges on the first said flanges, spacing members fixed to said drying element about the margins thereof and adapted to engage the drying surface of an adjacent tray and hold the trays in spaced relation, said spacing members comprising a vertical portion fixed to the face of said reinforcing flange, an offset shoulder engaging the edge thereof for supporting the same, a spacing portion, a bearing portion adapted to rest on the margin of a similar drying tray, and an offset guide portion depending from said bearing portion.

5. A drying tray for hides and the like comprising a sheet metal drying element having apertures therein for permitting the circulation of air therethrough, said drying element including marginal reinforcing flanges depending therefrom, and spacing members adapted to support the tray on and in spaced relation to a like adjacent tray, said spacing members comprising a vertical portion fixed to the face of said reinforcing flange, an offset shoulder engaging the edge thereof for supporting the same, a spacing portion, a bearing portion adapted to rest on the margin of a similar drying tray, and an offset guide portion depending from said bearing portion.

6. A drying tray for hides and the like comprising a sheet metal drying element having apertures therein for permitting the circulation of air therethrough, said drying element including marginal reinforcing flanges depending therefrom, return bent flanges on the edges of the first said flanges, means for spacing the tray from the drying surface of an adjacent tray, said spacing members comprising a vertical portion fixed to the face of said reinforcing flanges, an offset shoulder engaging the edge thereof for supporting the same, a spacing portion, a bearing portion adapted to rest on the margin of a similar drying tray, and an offset guide portion depending from said bearing portion.

7. A drying tray comprising a substantially flat drying element; and supporting and spacing members at each corner of the drying element, each said member including an angular upper flange embracing the corresponding corner of the drying element, an angular lower flange parallel to and outwardly spaced from the upper flange to embrace an upper flange of an adjacent lower tray, a spacer section parallel to and inwardly spaced from the upper and lower flanges, and upper and lower shoulders connecting the spacer section to the upper and lower flanges respectively, the upper shoulder serving as a seat for its associated drying

element and the lower shoulder serving as a seat for supporting the tray on an adjacent lower tray.

8. A drying tray comprising a substantially flat foraminous metallic drying element; and supporting and spacing members at corners of the drying element, each said member being formed from a single piece of metal and including an angular upper flange embracing the corresponding corner of the drying element, an angular lower flange parallel to and outwardly spaced from the upper flange to embrace an upper flange of an adjacent lower tray, a spacer section parallel to and inwardly spaced from the upper and lower flanges, and upper and lower shoulders interconnecting the spacer section with the upper and lower flanges respectively, the upper shoulder serving as a seat for its associated drying element and the lower shoulder serving as a seat for supporting the tray on an adjacent lower tray.

In witness whereof, I hereunto subscribe my name this 29th day of July, 1930.
